UNITED STATES PATENT OFFICE.

JAMES A. CROSS, OF DENVER, COLORADO.

VULCANIZER.

Application filed May 10, 1926. Serial No. 108,006.

This invention relates to improvements in the construction of vulcanizers of the type employed in the repair of automobile tires and tubes and has reference more particularly to the construction of an electrically heated apparatus of this type.

In repairing tires and tubes it is necessary to heat the material to a predetermined temperature for a given length of time so as to properly cure the rubber. If the temperature fails to reach the desirable value or exceeds it, the results are not the best. It is, therefore, very essential to be able to maintain the parts at the optimum temperature. Where steam is employed for heating a vulcanizer, the temperature can readily be determined by means of a pressure gage as the temperature is always the same for a given pressure absolute. It is, however, very much more convenient to obtain the heat by an electric heating element which may be built into the vulcanizer. It is evident, however, that when an electric heating element is used some thermoresponsive means must be employed to indicate the temperature and for this purpose it is customary to employ a thermometer. Where an electric heating element is employed and where a thermometer is used for determining the temperature, the operator must carefully observe the temperature and open and close the electric circuit in accordance with the temperature indications. It is evident that an electrically heated device would be much more conveniently operated if it were provided with an automatic mechanism for controlling the temperature and one of the objects of this invention is to produce an electric vulcanizer provided with such thermal control. The above and other objects that may become apparent as the description proceeds are obtained by means of a construction that I will now proceed to describe in detail, reference for this purpose being had to the accompanying drawing in which the invention has been illustrated and in which:

Fig. 1 is a top plan view of one of my improved electric vulcanizers;

Fig. 2 is a transverse section taken on line 2-2, Fig. 1;

Fig. 3 is a longitudinal section taken on line 3-3, Fig. 1; parts being broken away so as to better show the construction;

Fig. 4 is a diagram of the electric connections and the manner in which the electric circuit to the heater is made and broken; and

Fig. 5 is a transverse section through a tire retreading mould.

In Figs. 1, 2, and 3 a tube vulcanizer has been illustrated. This vulcanizer consists of a box shaped member of cast iron provided with a top 1 of considerable thickness, sides 2, 3 and ends 4 and 5. The top 1 has flanges 6 and 7 that extend beyond the end walls 4 and 5 in the manner shown in Fig. 3 and these flanges project over onto and rest upon the top of the end supports 8 and 9 which are secured to the ends 4 and 5 by means of bolts 10 and are spaced from the ends by means of plates 11 that extend below the lower edge of the ends so that they may be bent in the manner indicated by numeral 12. The end supports 8 are provided with feet 13 that rest upon a supporting surface and with up-standing ears 14 that are perforated for the reception of the pivot bar 15 to which levers 16 are both slidably and pivotally attached. These levers are bent in the manner indicated by numeral 17 and have a portion 18 that extends downwardly terminating in a perforated hub 19 through which the pivot bar 15 extends. Below the hubs 19 are projections 20 whose inclined ends 21 are adapted to engage the side 3 and act as stops when the levers are moved to the dotted line position shown in Fig. 2. The levers 16 are each provided with a longitudinal slot 22 through which the bolt 23 extends. These bolts have enlarged square heads 24 that are adapted to engage with the upper surface of the blocks 25. Helical compression springs 26 surround the bolts 23 and have one end in contact with the heads 24 and the other with the washers 27 and produce a force tending to move the bolt 23 downwardly (Fig. 2). A nut 28 secured to the ends of the bolts 23 acts as a stop for limiting the movement of the bolt in one direction. Pawls 29 are pivoted at 30 to the levers 16 and are provided with teeth 31 that are adapted to engage the sharp edge 32 of the top 1 for the purpose of holding the levers against movement against the force exerted by the spring 26. Each pawl has a handle 33 by means of which it can be manipulated. The material to be vulcanized is placed between the upper surface of the top 1 and the lower surface of the block 25 but has not been shown. The electric heater element consists of a plate of insulating material such as mica and which has been designated by numeral 34. Resistance wire 35 is coiled about this plate so as

to form at least two sections R and R¹ (Fig. 4). Mica plates 36 are applied to each side of the heater element which is clamped against the under surface of the top 1 by means of a plate 37 and bolts 38. An asbestos board 29 separates the plate 37 from the heater and serves as a heat insulator. The space below the plate 37 is filled with asbestos 40 that serves as a heat insulator that prevents the escape of heat downwardly and this material is held in place by means of a sheet metal bottom 41 that in turn is held in place by the flanges 12.

The temperature is determined by means of a pressure gage 42 which employs a Bourdon tube 43 whose interior is in communication with the pipe 44 that extends substantially the entire length of the top 1 in the lower surface of which it is embedded in the manner shown in Figs. 2 and 3. The end of the pipe 44 is closed by means of a plug 45. The pipe 44 is filled with water or some other suitable liquid which is vaporized by the heat. Since the temperature of saturated steam or vapor varies directly with the pressure, the scale of the gage 42 can be calibrated in degrees of temperature or of pounds of pressure as may be desired.

From Fig. 4 it will be seen that the resistance coils R and R¹ are connected to one pole of the source of electric supply, which has been indicated as a battery 46, by means of a conductor 47. A conductor 48 extends from the other pole of the battery to the spring conductors 49 and 50 which are normally in electrical contact with the terminals 51 and 52, respectively. From the terminals 51 and 52 conductors 53 and 54 extend to the ends of the resistance coils R and R¹. When the parts are in the position shown in Fig. 4 current will flow through both of the resistance coils. A switch 55 serves to open and close the circuit. When the pipe 44 becomes hot the liquid will be vaporized and placed under pressure and this pressure will cause the Bourdon tube 43 to straighten, as the pressure increases the lug 56 will move towards the screw 57 and will engage this screw when the temperature reaches the maximum value; after the lug 56 engages the screw 57 any increase in pressure will move the spring 49 upwardly and away from the terminal 51 thereby breaking the circuit to the coil R. The heat generated by the coil R¹ should be just about sufficient to make up for the heat losses so that the parts will retain their temperature. Should the temperature continue to increase after the coil R has been disconnected, the point of the screw 58 will engage the spring 50 and move it away from the terminal 52 thereby disconnecting the coil R¹. Should the temperature still rise, the contact 59 will soon reach the terminal 60 thereby short circuiting the battery through wires 48 and

61 and blowing the fuse 62. This short circuiting and blowing of the fuse is resorted to as a safety device because the fact that the temperature increases when both of coils R and R¹ are disconnected shows that there is something radically wrong.

In Fig. 5 I have shown a cross section of a tire vulcanizing mould which is built on the same principle but merely made in a different shape. The body 63 is preferably of cast metal and has electric heaters 64 embedded in the sides. A pipe 44^A that corresponds in function with pipe 44 connects with the pressure gage 42 and the operation is exactly the same as the one described.

I want to call particular attention to the automatic heat control mechanism which functions to disconnect the several heater coils one after the other so as to reduce the amount of current at each break and to gradually reduce the heat. The means for clamping the work which comprises the levers 16, pawl 29, bolt 23, etc., are also believed to be novel in this combination.

Having now described the invention what I claim as new is:

1. In a thermoresponsive device adapted to control an electric heater, a closed chamber containing a liquid, a Bourdon tube pressure indicator operatively connected with said chamber so as to measure the pressure therein, an electric heater comprising two separate heating elements connected in series, and a source of electric current having one terminal connected to the common connection of said heater element, two resilient springs, each having one end stationary and the other end movable, the stationary ends being connected with the other terminal of the battery, a stationary contact for the free end of each of said springs and on which the free ends of the springs normally rest, the free ends of said heaters being each normally connected with one of said contacts, means on said Bourdon tube for engaging one of said springs and for moving it away from its contact when the pressure exceeds a predetermined amount and means carried by the last named spring for engaging the other spring and for moving it out of contact with its stationary contact when the pressure exceeds another predetermined amount.

2. In a thermoresponsive device adapted to control an electric heater, a closed chamber containing a liquid, a Bourdon tube pressure indicator operatively connected with said chamber so as to measure the pressure therein, an electric heater comprising two separate heating elements connected in series, and a source of electric current having one terminal connected to the common connection of said heater element, two resilient springs, each having one end stationary and the other end movable, the stationary ends being connected with the other

terminal of the battery, a stationary contact for the free end of each of said springs and on which the free ends of the springs normally rest, the free ends of said heaters being each normally connected with one of said contacts, means on said Bourdon tube for engaging one of said springs and for moving it away from its contact when the pressure exceeds a predetermined amount and means carried by the last named spring for

engaging the other spring for moving it out of contact with its stationary contact when the pressure exceeds another predetermined amount, a fuse in the lead from the battery to the springs and means for short circuiting the battery through the fuse if the pressure continues to increase after both springs have been moved to circuit opening position.

In testimony whereof I affix my signature.

JAMES A. CROSS.
